UNITED STATES PATENT OFFICE.

WILLIAM F. MORTON, OF NEW HAVEN, CONNECTICUT.

DESIGN FOR A WHEEL-HUB BAND.

SPECIFICATION forming part of Design No. 27,831, dated November 9, 1897.

Application filed September 14, 1897. Serial No. 651,681. Term of patent 14 years.

To all whom it may concern:

Be it known that I, WILLIAM F. MORTON, a citizen of the United States, residing at New Haven, in the county of New Haven and State of Connecticut, have invented and produced a new and original Design for Wheel-Hub Bands; and I do hereby declare the following to be a full, clear, and exact description of the design, reference being had to the accompanying drawings, forming part thereof.

In the drawings, Figure 1 is an end view of a wheel-hub embodying my design. Fig. 2 is a side view of the same. Fig. 3 is a cross-section taken at line X X of Fig. 1.

As shown in the drawings, the leading feature of my design is a wheel-hub band A, having at its inner end an annular offset or bead *a*, the exterior surface of which offset or bead is rounded transversely and the interior surface of which is composed of the annular wall *b*, standing at substantially a right angle to the axis of the band, and the annular wall *c*, extending from said wall *b* to the in-

ner end of the band at a slightly obtuse angle to the wall *b*, as shown in Fig. 3. The exterior surface of the band between said offset or bead and its outer end is shown in the drawings as being a smooth surface without projections or indentations; but such surface is not material to my design, the essential feature of which is a wheel-hub band having at its inner end an annular offset or bead the inner surface of which is composed of two annular walls arranged substantially as shown.

What I claim as new, and desire to secure by Letters Patent, is—

The design for a wheel-hub band substantially as herein shown and described.

In testimony whereof I affix my signature in presence of two witnesses.

WILLIAM F. MORTON.
